INSOLE AND METHOD OF MANUFACTURING SAME

Filed Feb. 28, 1929

UNITED STATES PATENT OFFICE

SIDNEY R. BLAKELY, OF JAMAICA PLAIN, MASSACHUSETTS

INSOLE AND METHOD OF MANUFACTURING SAME

Application filed February 28, 1929. Serial No. 343,405.

- My present invention relates to insoles, and more particularly to a novel and improved insole particularly adapted for use in the manufacture of boots or shoes, the insole of the present application being an alternative of and an improvement on the insoles illustrated, described and claimed in my prior and copending application Ser. No. 339,811, filed Feb. 14, 1929.
- 10 The insole of the present application, also, is adapted and intended to be used in conjunction with the novel last of my copending application Ser. No. 339,812, filed Feb. 14, 1929.
- 15 Insoles in which the present invention is embodied are equally applicable for use in turn, welt or McKay shoes, or shoes manufactured according to well known cemented processes, and while the drawing of the present application illustrates an insole primarily adapted for use in McKay shoes, it will be appreciated and understood that this is for illustrative purposes only and that I am not limited thereto.
- 20 25 An important object of the present invention resides in the provision of an insole with an abrupt break therein at the rear of the shank portion, this break being defined by a substantially vertical wall against which the foot of the wearer will bear.
- Another object of the invention resides in providing a novel shank piece, constructed and arranged to have a portion at the rear thereof which will substantially abut against said wall of the insole and reinforce the said wall, retaining it in shape against the weight of the wearer.
- 30 35 Another object of the invention resides in providing, in said insole, and before assembly in the shoe, a rounded heel seat which, combined with the aforesaid substantially vertical wall, will form a deep pocket, in which, in the completed shoe, is adapted to be fitted a heel pad of considerable depth, and of sufficient softness or cushioning capacity to allow the heel of the wearer to press said pad to a sufficient extent to allow the forward part of the heel of the wearer to bear against the upper edge of said wall.
- 40 45 50 Another object of the invention resides in affixing, to the heel portion of said insole, and before the molding operation or step to cup the same, a reinforcing layer or plate, preferably of non-metallic material, of sufficient body and stiffness to retain the rounded contour once same has been molded in the heel portion. This heel piece or plate is constructed with a rectangular recess therein to receive the heel end of a metallic shank stiffener, so that this heel end of said stiffener will be flush or substantially flush with the exposed surfaces of said heel piece or plate, thus preventing any discomfort to the wearer of the shoe and will also provide an anchorage for the heel end of said stiffener.
- In carrying out my present invention I utilize an insole blank of greater length than the length of the completed insole, this increased length being sufficient to allow for the formation of the aforesaid wall at the rear of the shank portion.
- I believe that an insole constructed as above is novel, and I have therefore claimed the same broadly in the present application.
- I also believe that the method of manufacturing said insole, above briefly described, is novel, and said process is therefore also described and claimed in the present application.
- I furthermore believe that the particular shank piece illustrated and described herein is novel, and said shank piece is therefore also claimed in the present application.
- The above and other objects of the invention, details of construction, combinations and advantages, will be hereinafter more fully pointed out, described and claimed.
- Referring to the drawings, illustrating a preferred embodiment of the present invention,
- Fig. 1 is a bottom plan view of an insole blank;
- Fig. 2 is a side elevation of said blank after application of the heel layer and cupping thereof;
- Fig. 3 is a bottom plan view of the blank as thus far prepared;
- Fig. 4 is a side elevation of the blank of Fig. 2 positioned on a last preparatory to breaking;

Fig. 5 is a fragmentary medial sectional view of the rear of the shank and heel portion of said blank after being broken or shortened;

5 Fig. 6 is a bottom plan view of the structure illustrated in Fig. 5;

Fig. 7 is a perspective view of the novel shank piece preferably utilized;

10 Fig. 8 is a medial sectional view of the blank after application and temporary securing of the shank piece;

Fig. 9 is a perspective view of the blank after breaking; and

15 Fig. 10 is a fragmentary medial sectional view of the completed insole, illustrating application of a metallic shank stiffener thereto.

Referring now to the drawings for a particular description of the invention, 1 designates an insole blank, preferably of leather, formed to the shape of an insole, but of slightly greater length than the length of the completed insole.

This blank may be provided, on its bottom surface, with a series of transverse slits 2, for flexibility, as is usual. Onto the heel portion of said blank I then apply a layer 3 of non-metallic material, and preferably fibrous material, such as leather. Wood may be utilized if desired. This layer 3 may be secured to the heel portion of the blank by adhesive, or by staples 4, or both, and this heel portion, including the layer 3, is then subjected to a molding operation which will 35 give a rounded inner cup, as illustrated at 5, this cup or concavity being rounded to a predetermined contour.

In the heel piece or layer 3 I provide a recess 8, preferably rectangular in shape, the 40 purpose of which will be hereinafter more fully described.

The blank as thus far completed, is then applied to a last 6, this last having a substantially vertical wall 7 thereon, and the 45 blank is then hammered or beaten to conform to the shape of the said last. This operation will break the blank, at the rear of the shank portion thereof, and will form a substantially vertical wall 9 therein, corresponding 50 to the wall 7 on the last.

This breaking operation also will shorten the blank 1, bringing it to desired length.

If desired, this breaking operation may be performed in a machine, prior to application to the last, in which event the blank 55 would appear as illustrated in Fig. 9, shortened and ready for application to said last, but the preferred method is as above described, viz, breaking the same directly on 60 the last 6.

The beating or hammering of the blank 1 will also form therein an arch in the shank portion, as clearly illustrated in Figs. 5, 8 and 10. Subsequently to this operation, I then 65 apply my novel shank piece 10, this piece

tapering from a relatively thin edge 11, to the thick end 12, the height of the thickened end 12 being preferably substantially the same as the height of the wall 9 in the insole. When the shank piece 10 is applied to the blank, it may be secured thereto by adhesive, or by a tack 13 or both. The shank piece 10, also, will assume the arch shape of the shank portion of the blank 1, being beaten to this shape if necessary.

70 The insole is now ready to receive a metallic shank stiffener 14, the heel end of which will be seated in the recess 8 in the heel piece 3, being securely anchored therein against transverse movement and against longitudinal movement toward the heel, the heel piece 3 being preferably of approximately the same height as the thickness of the shank stiffener or arch support 14 so that said arch support will be substantially flush with said heel piece.

75 The edges of the heel piece 3 are preferably skived or beveled, as are also the sides of the shank piece 10, to effect a better fitting of the insole within the completed shoe.

80 The pocket formed in the insole is capable of receiving a relatively deep heel pad or cushion, which may have a partially or substantially straight front wall adapted to abut against the vertical wall 9, said wall 9 85 preferably extending squarely across the front of the heel portion.

85 Thus, in the completed shoe, when the weight of the wearer is put in the shoe, the heel pad will compress sufficiently to allow the forward part of the heel of the wearer to bear or abut against the wall 9, thus affording a firm grip for the heel of the wearer in the heel part of the shoe, and preventing the throwing of the weight of the wearer entirely on the ball and toes of the foot, as is done in existing types of shoes. The wall 9 will be strengthened and reinforced by the thick end 12 of the shank piece 10, preventing any breaking down of the said wall 9 during walking or wearing of said shoes.

90 The utility, efficiency, strength and advantages of my novel insole will be apparent to those skilled in the art, and when incorporated in the shoe of my said copending application, 100 will result in great comfort and ease to the wearer thereof, eliminating many foot and orthopedic troubles occasioned by present 105 shoes of the high heel type.

110 While I have necessarily described my present invention somewhat in detail, it will be appreciated that I may vary the size, shape and arrangement of parts within reasonably wide limits without departing from the spirit of the invention.

115 My invention is further described and defined in the form of claims as follows:

120 1. An insole for use in the manufacture of boots and shoes, having an abrupt break 125 therein at the rear of the shank portion 130

thereof, said break being defined by a substantially vertical wall, and a layer of reinforcing material along the shank portion thereof, the rearmost edge of said layer 5 being of substantially the same height as said wall.

2. An insole for use in the manufacture of boots and shoes, having an abrupt break therein at the rear of the shank portion thereof, said break being defined by a substantially vertical wall, a layer of reinforcing material on the heel portion thereof, said heel portion and said reinforcing layer having a cup formed therein, and a layer of reinforcing material along the shank portion thereof, said shank portion and said reinforcing layer having an arch formed therein, the rearmost edge of said shank layer being of substantially the same height as said wall.

10 3. An insole for use in the manufacture of boots and shoes, having an abrupt break therein at the rear of the shank portion thereof, said break being defined by a substantially vertical wall, a layer of reinforcing material on the heel portion thereof, said heel portion and said reinforcing layer having a cup formed thereon, said heel layer having a recess therein to receive the heel end of an arch supporter, and a layer of reinforcing

15 material along the shank portion of said insole, said shank portion and said reinforcing layer having an arch formed therein.

4. An insole for use in the manufacture of boots and shoes, having an abrupt break therein at the rear of the shank portion thereof, said break being defined by a substantially vertical wall, a layer of reinforcing material on the heel portion thereof, said heel portion and said reinforcing layer having a cup formed therein, said heel layer having a recess therein to receive the heel end of an arch supporter, a layer of reinforcing material along the shank portion of said insole, said shank portion and said reinforcing layer having an arch formed therein, and the rearmost edge of said shank layer being of substantially the same height as said wall.

20 5. That improvement in the art of manufacturing insoles, which consists in subjecting a blank of greater length than the completed insole to a breaking operation, whereby a substantially vertical wall will be produced at the rear of the shank portion of sufficient height to reduce the said insole to desired length, and applying a shank piece to said insole, the rearmost edge of said shank piece being of substantially the same height as said wall.

25 6. That improvement in the art of manufacturing insoles, which consists in forming a substantially rectangular recess in a layer of reinforcing material to receive the heel end of an arch supporter, applying said layer to the heel portion of an insole blank, and

concaving said heel portion and said reinforcing layer.

7. That improvement in the art of manufacturing insoles, which consists in forming a substantially rectangular recess in a layer of reinforcing material to receive the heel end of an arch supporter, applying said layer to the heel portion of an insole blank of greater length than the completed insole, and subjecting said blank to a breaking operation, whereby a substantially vertical wall will be produced at the rear of the shank portion of sufficient height to reduce said blank to desired length.

8. That improvement in the art of manufacturing insoles, which consists in forming a substantially rectangular recess in a layer of reinforcing material to receive the heel end of an arch supporter, applying said layer to the heel portion of an insole blank of greater length than the completed insole, subjecting said blank to a breaking operation, whereby a substantially vertical wall will be produced at the rear of the shank portion of sufficient height to reduce said blank to desired length, and applying to the shank portion of said blank a reinforcing layer having the rearmost edge thereof of substantially the same height as said wall.

9. That improvement in the art of manufacturing insoles, which consists in forming a substantially rectangular recess in a layer of reinforcing material to receive the heel end of an arch supporter, applying said layer to the heel portion of an insole blank of greater length than the completed insole, subjecting said blank to a breaking operation, whereby a substantially vertical wall will be produced at the rear of the shank portion of sufficient height to reduce said blank to desired length, applying to the shank portion of said blank a reinforcing layer having the rearmost edge thereof of substantially the same height as said wall, and arching the said shank portion of said blank and said shank reinforcing layer.

In testimony whereof, I have signed my name to this specification.

SIDNEY R. BLAKELY.
